UNITED STATES PATENT OFFICE.

GEORGE W. GILLESPIE, OF PUNXSUTAWNEY, PENNSYLVANIA.

APPARATUS FOR CASTING SASH WEIGHTS.

Application filed May 25, 1921. Serial No. 472,384.

To all whom it may concern:

Be it known that I, GEORGE W. GILLESPIE, a citizen of the United States, residing at Punxsutawney, in the county of Jefferson 5 and State of Pennsylvania, have invented certain new and useful Improvements in Apparatus for Casting Sash Weights, of which the following is a specification.

This invention relates to molds and patterns for metal casting and more especially for the production of seamless sash weights.

The objects of the invention are:

First, to so construct cooperating pattern, draw plate and core as to form a finished mold with the minimum of steps, said mold adapted to cast a maximum number of uniform, flawless and seamless sash weights with well formed and rounded ends and having at one or both of said ends smooth 10 staples firmly attached or incorporated with the cast metal and identifying characters designating the load of the sash weight.

Second, to construct the cooperating parts of the apparatus to form the mold so that 15 the core is not inserted or projected into the mold, cope, or drag, thereby avoiding any possibility of detaching or displacing the sand of the mold or pushing into the mold any sand after the pattern is withdrawn 20 during the adjustment or placement of said core and insuring a smooth mold throughout and perfect castings.

Third, to construct the cooperating parts of the apparatus so that when the pattern is 25 withdrawn from the mold and the core is put in position, the mold is complete and the core is not pushed into position or into the mold and forms the cope of the complete mold.

Fourth, to construct the parts of the apparatus so that when the mold is complete, and the core forming the cope is in place, the gates for conveying the molten metal are removed from the ends of the mold 40 thereby enabling the casting of a sash weight having finished, smooth and well formed ends without further manipulation.

Fifth, to construct a pattern having a plurality of separable and removable units 45 cooperating with a draw plate in such a manner, so that the number, size and type of sash weight patterns to be molded and cast in any particular flask can be easily and quickly varied without skilled labor 55 and in a minimum of time.

Sixth, to form a draw plate with gate

forming instrumentalities integrally connected therewith and arranged in such a manner with the cooperating pattern, so that the gates enter the completed pattern 60 mold at a point removed from the section of said mold corresponding to the rounded end of the finished sash weight.

Seventh, to provide a core box adapted to produce a combined cope and core provided 65 with one or more staples adapted to be embedded or incorporated with the ends of the sash weight castings and also means to form on the ends of said castings load indicating characters.

Eighth, other objects and advantages of the invention will appear from the detailed construction and arrangement of the apparatus and manner of using the same to be 70 hereinafter described.

The invention consists of structural characteristics and relative arrangements of parts which will be hereinafter more fully disclosed and particularly pointed out in 75 the appended claims.

In the two sheets of drawings in which 80 similar reference characters indicate the same parts in the several figures.

Figure 1, is a longitudinal section of the mold within the flask after the metal has 85 been poured.

Figure 2, is a bottom plan view of the core.

Figure 3, is a longitudinal sectional view 90 of the flask with the pattern in place to receive the sand and taken on line III—III of Fig. 4.

Figure 4, is a top plan view of Fig. 3.

Figure 5, is a top plan view of the core box for making the core shown in Fig. 2. 95

Figure 6, is a section on line VI—VI of Fig. 5.

Figure 7, is a section of the draw plate and taken on line VII—VII of Fig. 4.

Figure 8 is a section of the core and taken 100 on line VIII—VIII of Fig. 2.

Figure 9 is a perspective view of a finished sash weight having a staple at each end as made by the apparatus, and

Figure 10, is a perspective view of a 105 sash weight having only one end provided with a staple and of shorter length and reduced weight.

Referring to Figs. 1, 3 and 4, 10 is the flask which in this case is square and rectangular in cross-section and of a size to 110 cast four sash weights and while I have illus-

trated the invention as applied in making four, this number may be decreased or multiplied without in any way changing the essential and novel features of the present invention. One end of the bore or inner sides of the flask 10 is inclined outwardly as shown at 11, for the purpose of receiving the correspondingly shaped draw plate and frame carrying the patterns to be presently described. 12 is a frame having one or a plurality of threaded recesses 13 which are engaged by the threaded ends 13' of a series of removable patterns 14 which in the present instance are cylindrical in shape and rounded at their detached ends 15 as shown in Figs. 3 and 4. Said patterns 14 may be of different lengths and provided at their ends with or without characters 16, and oppositely disposed circular recesses 17 for the reception of staples 18 as desired, depending upon weight and variety of sash weights to be cast. 19 is a draw plate having one or more openings 20 similarly disposed and arranged as the threaded recesses 13' in frame 12 and of such contour and diameter as to snugly fit around the patterns 14 and permit said patterns to readily slide through said openings 20 and be withdrawn from the draw plate 19, when so desired. Attached to the inner side and centrally disposed on the draw plate is a projection or enlargement 21 which is preferably of star-shape, see Figs. 3 and 7, and having its outer ends in juxtaposition and in sliding contact with the cylindrical side of each pattern 14, near the end secured to the frame 12 as shown in Figs. 3 and 4, and adapted to form the gates 21', see Fig. 1, in the mold as will be hereinafter more fully understood. The outer edges or sides of the frame 12 and plate 19 are beveled at such an angle as to properly fit within the outwardly inclined inner sides 11 of the flask 10 and assume the position indicated in Fig. 3.

22 is a bottom or floor plate common in this class of inventions for supporting the weight of the flask and properly sustaining the frame 12 and attached patterns 14 surrounded by the draw plate 19 within the flask 10 as shown in Fig. 3.

Referring to Figs. 5 and 6, 23 is the core box which is provided with a recess 24, preferably square in shape and of a depth corresponding to the combined thicknesses of the frame 12 and draw plate 19, and its side walls 25 inclined at such an angle as to form a core of the same size, shape and beveled edges as the combined and superimposed frame 12 and plate 19 as shown in Fig. 3. Said core box 23 is provided on the bottom 23' of its recess 24 with a plurality of circular and rounded projections 26, which are so disposed and arranged as to register with the openings 20 in the draw

plate 19, and each of said projections 26 may or may not be provided with a character 27 and diametrically and oppositely disposed sockets 28 adapted to removably and vertically support a staple 29, as indicated in dotted lines in Fig. 6. On the bottom 23' and center of the recess 24 is secured a pin 30, adapted to be engaged by the recessed and smaller end of a removable core box section 31, preferably frusto-conical in shape and adapted to form the sprue hole or opening 32, see Fig. 8, in the combined core and cope 33 to be presently described.

The manner of using the core box shown in Figs. 5 and 6 to produce the combined core and cope 33 shown in Fig. 8 is as follows: The staples 29 are inserted in the sockets 28 and the core section 31 is adjusted and made to engage the pin 30 as shown in Fig. 6, said core box 23 is then properly filled with any suitable mixture for core making and baked as is common in this class of inventions and needs no further disclosure, and after said baking the removable core section 31 is taken out and the core box 23 inverted, and a core 33 as shown in Figs. 2 and 8, is obtained in which a central sprue hole or opening 32 is provided, and the curved portion of each of the staples 29 is firmly embedded and immovably held in the body of the combined core and cope 33 with its straight ends projecting therefrom at a section formed with a semi-spherical recess or depression 34, having a load designating character 35, if so desired, as clearly illustrated.

The parts being constructed, as herein described, the manner of assembling and using the same is as follows:

Assuming the flask 10 shown in Fig. 3 to be inverted and the end having the inner inclined sides 11 is at the top, and the frame 12 with its previously determined and selected sash weight patterns 14 attached thereto and draw plate 19 have been assembled as shown in Fig. 3, said draw plate 19, frame 12 and patterns 14 are inserted in said flask and the floor or bottom plate 22 is placed on top. The flask 10 containing said draw plate 19, frame 12, floor plate 22, and attached patterns 14 is then inverted and its contents assume the position shown in Fig. 3. Staples 18 are then inserted in the recesses 17 at the ends 15 of said patterns 14 as desired. When the sand is placed within the flask 10 and carefully rammed about the patterns 14, and after so rammed the superfluous sand is scraped off and a plate 36, such as shown at bottom of Fig. 1 is placed in position to register with the open top or end of flask 10. The flask 10 is then again inverted, the frame 12 after slightly tapping it, is carefully lifted from the end of the flask, which simultaneously withdraws all the patterns 14 from the sand and

through the openings 20 in the drawplate 19, and leaves embedded in the sand at the bottom of each pattern mold 37 the curved portions of all previously placed staples 18 with their straight ends projecting into the molds, as shown in Fig. 1, and also an impression of the designating characters 16, as will be readily understood. Should it be found that through some accident or inadvertence any foreign substance or sand has been detached or fallen into the molds 37, the flask 10 with its mold and draw plate 19 can be turned over and said sand or substance can readily be made to drop out, and the flask returned to its former position without in any way injuring the mold. After the foregoing operations the draw plate is removed from the flask and the combined core and cope 33 are shown in Fig. 8, is inserted into beveled end 11 of the flask and resting on the molded sand in the position shown in Fig. 1, which completes the mold and ready to receive the molten metal. The molten metal is poured into the sprue hole or opening 32 and passes by way of the gates 21' into each of the pattern molds 37 and said metal at either or both ends of said molds, after cooling becomes firmly united with the staples 18 and 29 at said ends and embedded in the finished sash weights 39 and 40 as shown in Figs. 1, 9 and 10, in which Fig. 9 shows a sash weight with a staple at each of its ends, while Fig. 10 shows a staple at only one end; and said sash weights may be also formed with designating characters 41 at either or both ends, depending on what characters 16 and 27 are employed in the completed mold, and if lighter or heavier sash weights are desired 40 the removable patterns 14 can be quickly detached from the frame 12 and others readily substituted therefor, as will be fully understood and needs no further disclosure.

After the mold is cooled and the metal set, it is removed from the flask when by the usual method of breaking away the sand from the casting, the combined cope and core will readily disintegrate and leave the staples 18 and 29 firmly embedded and attached to the cast sash weights, and the superfluous metal attached to said group of sash weights formed by sprue opening and gates can be quickly detached therefrom without in any way marring the contour or smoothness of the ends or sides of the sash weights, for the reason that the gates are of small cross-sectional area and connect with the sides of the sash weights and removed from their ends.

60 The cast sash weights can be finished by tumbling in a rumble, if so desired, when

uniform and seamless sash weights will have been produced having well rounded and smooth ends provided with rigid staples and weight designating characters. 65

From the foregoing disclosure of the construction and operation of the improved apparatus, it will be seen that all the objects and advantages recited in the statement of invention have been fully and efficiently 70 carried out, and while I have shown my preferred form, many changes will readily suggest themselves and yet lie within the scope of the structure as expressed in the claims, whether the apparatus is operated manually 75 or mechanically, and I also contemplate using the same, whether two, four, or any other number of sash weights are cast in a single flask and making of sash weights having staples at one or both ends, or with 80 weight designating characters at one or both ends or without such characters.

What I claim is:

1. In a mold for the casting of sash weights, the combination of a green sand 85 drag containing the major portions of the mold cavities and a dry sand combined cope and core resting on said green sand drag and provided with a pouring gate and cavities registering with the mold cavities and 90 all enclosed in the same one-piece flask.

2. In the mold for the casting of sash weights, the combination of a green sand drag containing the major portions of the mold cavities and a staple at the bottom 95 of a mold cavity and a dry sand combined cope and core resting on said green sand drag and provided with a pouring gate and cavities registering with the mold cavities and all enclosed in the same one-piece 100 flask.

3. In a mold for casting sash weights, the combination of a green sand drag containing the major portions of the mold cavities and a dry sand combined cope and core 105 resting on said green sand drag and provided with a pouring gate, and cavities and staples in said cavities registering with the mold cavities and all enclosed in the same one-piece flask. 110

4. In a mold for casting sash weights, the combination of a green sand drag containing the major portions of the mold cavities and a dry sand combined cope and core resting on said green sand drag and provided with a pouring gate, and cavities and weight designating characters and staples in said cavities registering with the mold cavities and all enclosed in the same 115 one-piece flask. 120

In testimony whereof I affix my signature.
GEORGE W. GILLESPIE.
